SCAVENGING OF TWO-CYCLE ENGINES

Edward S. Dennison, Swarthmore, Pa., assignor
to Westinghouse Electric & Manufacturing
Company, East Pittsburgh, Pa., a corporation
of Pennsylvania

Application December 14, 1933, Serial No. 702,403

2 Claims. (Cl. 123—65)

My invention relates to two-cycle engines and it has for an object to provide for an improved exhaust and scavenging arrangement so that effective scavenging may be had with a relatively large effective working stroke of the engine. It is old to have a two-cycle engine cylinder provided with opposed scavenging air and exhaust ports; however, this simple arrangement is not very effective unless the piston is modified to provide for deflection of the air in order to prevent transverse passage of the air directly across the cylinder and out the exhaust ports. A second arrangement has been used wherein a partial belt of scavenging air ports is arranged below a similar partial belt of exhaust ports, the air crossing the cylinder and being deflected by the opposite imperforate cylinder wall upwardly until deflected by the head so as to pass downwardly to the exhaust ports, the air path being substantially a loop wherein the outlet is superposed with respect to the inlet. An objection to the second arrangement is that the provision of an imperforate cylinder wall to deflect the air upwardly necessitates partial port belts with the result that the ports have to be made higher than would be the case if they extended completely around the cylinder, and, therefore, to the extent that they have to be made higher, to that extent is the working stroke lessened. A third arrangement has been proposed which constitutes an improvement over the first type in that the air ports are directed radially toward a center disposed eccentrically with respect to the cylinder axis and variously inclined to secure upward travel of the air at one side of the cylinder, the air being deflected downwardly to the other side by the cylinder head and passing downwardly at the latter side to exhaust ports disposed in opposed relation with respect to the air ports; however, this type of construction is also objectionable because of the necessary port height and the consequent lessened effective engine stroke as compared to an arrangement wherein complete belts or ports are provided. It is also old to have both scavenging and exhaust ports extend around the full perimeter of the cylinder, the scavenging ports radiating from the cylinder axis. By this means, it is intended to produce a central fountain of air moving upwardly, while the exhaust gases are forced downwardly in the annular space between the air column and the cylinder wall; however, this arrangement suffers from instability unless the momentum of air from each port is identical, which practically it cannot be, with the result that the

air column is thrown off center in an irregular and indeterminate way and undesirable mixing of air and exhaust gases results.

In accordance with my invention, I provide a complete belt of exhaust ports and a complete belt of scavenging air ports arranged immediately below the exhaust ports, with the result that a minimum height of ports is involved and a large effective working stroke is preserved; and, to impart the desired directional effect to the air, the air ports radiate from a center which is eccentric to the cylinder axis so that the resultant velocity effect of the entering air produces an upwardly moving eccentric column of air disposed toward the side of the cylinder nearest to the eccentric center, the air passing upwardly and being deflected downwardly to push products of combustion out the exhaust ports. By directing the air to a locus near one wall, the upward moving column is caused to occupy roughly one-half of the cylinder section while exhaust gases occupy the other half and any difficulty because of instability of the upwardly-moving column, as above referred to, is avoided by positively directing the flow to a limited region adjacent to one wall. As the exhaust ports are arranged as a complete belt, there is no opportunity for dead spaces, and, immediately upon uncovering thereof by the piston, there is ample area all the way around for the outflow of products of combustion. In brief, my invention possesses the advantage of stability of the second and third arrangements aforesaid without the disadvantages of excessive port height and imperforateness of a cylinder wall and the advantage of minimum cylinder length required for the ports without the disadvantage of instability of the fourth arrangement. Therefore, a further object of my invention is to provide a two-cycle cylinder with complete belts of exhaust and scavenging air ports, with the scavenging air ports arranged immediately below the exhaust ports and radiating from a center eccentric to the cylinder axis to secure such flow of air as to effectively evict products of combustion from the cylinder.

If it is desired to change the location of the resultant air column with respect to the interior of the cylinder, this may be achieved by relative inclination of the air ports; for example, if the air port or ports at minimum radius with respect to the eccentric center are inclined upwardly, the air entering through the remainder of the ports is rendered more effective to position the resultant column nearer to the side of the cylinder at the upwardly inclined ports. Ac-

cordingly, a further object of my invention is to provide a cylinder having complete belts of exhaust and scavenge air ports with the scavenge air ports radiating from a common eccentric center and with one or more ports inclined upwardly.

A further object of my invention is to relate my improved scavenge port arrangement to the engine so as to obtain the most effective operation, this being done by having the eccentric centers of the scavenge ports arranged in the plane of the crank shaft axis.

These and other objects are effected by my invention as will be apparent from the following description and claims taken in connection with the accompanying drawings forming a part of this application, in which:

Fig. 1 is a vertical sectional view showing my improved scavenging arrangement;

Fig. 2 is a horizontal sectional view taken along the line II—II of Fig. 1 and showing the scavenge air ports;

Fig. 3 is a sectional view taken along the line III—III of Fig. 1 and showing the exhaust ports;

Fig. 4 is a sectional view of a modified arrangement wherein one or more air ports are inclined inwardly and upwardly;

Fig. 5 shows a plurality of cylinders grouped so that the scavenge port eccentric centers are in a plane of the longitudinal center line of the engine;

Fig. 6 is a view similar to Fig. 2 but showing a modified arrangement of scavenge ports;

Fig. 7 shows a further modified scavenge port arrangement;

Fig. 8 shows a further modified arrangement of exhaust ports; and

Fig. 9 is a diagrammatic view illustrative of a flow principle involved.

Before taking up a description of features of the invention in detail, certain principles and objectives will be considered. A full perimeter of both scavenge and exhaust ports is desirable to avoid dead spaces and to increase the effective stroke of the engine, this arrangement minimizing the portion of the stroke used for the exhaust and scavenging process. Also, the air should be so controlled that it flows up at one side of the cylinder and down at the other, as this produces more orderly scavenging and provides a minimum area of contact of the upwardly and downwardly moving columns, and, therefore, minimizes the admixture of air and exhaust gases. The latter point will be clear from diagrammatic Fig. 9. If the air is assumed to move upwardly as a central column, then the downwardly moving column would be a cylinder thereabout, the contact being a circle indicated at *a*. On the other hand, where the upwardly column moves up at one side of the diametral plane *b* and down at the other, the area of contact of the columns is very much less and is a minimum. In the first case, the cylindrical contact *a* would be 2.22 times the diametral contact *b*. In my improved scavenging arrangement, the operation is such that low, or substantially diametral, contact occurs.

In Figs. 1 and 2, I show an engine cylinder 16 having a piston 11 therein, the cylinder 16 having a head construction 12 provided with a fuel injection device 13 of any suitable type.

The cylinder is provided with a complete belt of exhaust ports 15 which are radially disposed with respect to the cylinder axis 16. Immediately below the ports 15, the cylinder is provided with a complete belt of scavenge air ports 17 which

are disposed substantially radially with respect to a center 18 which is eccentric to the cylinder 16.

An exhaust manifold 20 receives products of combustion leaving the ports 15 and a scavenge air manifold 21 supplies scavenge air through the ports 17 to evict products of combustion from the cylinder. In operation, and near the end of a power or working stroke, the piston 11 first uncovers the exhaust ports 15, whereupon there follows a drop in pressure of the combustion gases and outflow at high velocity of products of combustion through all of the ports 15, the complete belt of exhaust ports providing for highly effective action of this kind, while, at the same time, requiring minimum cylinder length for accommodation of the ports. As soon as the scavenge air ports 17 begin to become uncovered, then the scavenging air is effective to drive products of combustion out through the exhaust ports. 20

As the exhaust ports 15 and the scavenge air ports 17 are arranged as annular belts extending completely around the cylinder and as the ports of each belt are arranged as close together as possible consistent with strength of the cylinder and cooling thereof and as the belts are arranged close together, it will be apparent that a minimum extent of cylinder height or length is used to provide the ports, with the result that the effective working stroke is maintained at a maximum. 30

As will be seen from Fig. 3, the annular belt of exhaust ports radiate from the cylinder axis, thereby providing for maximum discharge area, minimum cylinder length for their accommodation and effective discharge. On the other hand, as may be seen from Fig. 2, the scavenge air ports 17 radiate from an eccentric center 18 so as to secure, due to the resultant velocity of air entering through the ports 17, a column of air 40 which moves upwardly at or toward the side of the cylinder having ports of minimum radius with respect to the eccentric center, the column of air moving upwardly and being deflected by the head 12 for movement downwardly at or 45 toward the other side of the cylinder to evict products of combustion through the exhaust ports.

While all of the scavenge air ports may be disposed horizontally, the arrangement thereof radially with respect to an eccentric center providing for the aforementioned flow effects given to the air, as shown in Fig. 4, the column of air may be caused to move upwardly more closely bunched to the side of the cylinder by inclining 55 inwardly and upwardly one or more air ports, indicated at 17a. Also, the inclined ports are advantageous in a directive sense.

In Fig. 5, I show a preferable arrangement of cylinders 16 and an air manifold or box 22, which communicates with the scavenge ports 17 of each cylinder, the cylinders being so disposed that the eccentric centers 18 fall on the longitudinal center line of the engine. Some throttling occurs in the regions 23 between adjacent cylinders; and, to 65 avoid any injurious effect because of lack of flow balance, as would be the case if the cylinders were placed so that the relation of the port to the manifold was a random one, the cylinders are placed so that the eccentric centers 18 fall 70 on the longitudinal center line of the engine, whereby the flow from each side toward the eccentric centers is symmetrical and upward flow of air in each cylinder is better controlled to minimize the admixture of scavenge air with 75

gases. The symmetrical flow of air into the cylinders on this account is further assisted by the provision of equal flow areas 24 at each side of each cylinder.

5 Fig. 6 shows an arrangement wherein the scavenge ports 17b have their center lines tangent to a circle 26, the effect of this arrangement being to give a swirling motion to the air to aid in combustion.

10 If the piston wrist pin bore is open at the ends, it may cause by-passing of air from the scavenge to the exhaust ports. This may be avoided by omitting either or both the scavenge and exhaust ports which would register with the wrist pin bore. Furthermore, wrist pin axes are necessarily 15 in the plane of the engine longitudinal center line. Accordingly, the principle of the arrangement in Fig. 5 may be employed, the eccentric centers being in the engine longitudinal center line and the 20 cylinders being left sufficiently blank to either side of the center line, as shown in Fig. 7 at 27 and 28, to avoid any by-passing effect of the wrist pin bore indicated in dotted lines at 29, the two sets of scavenge ports 17c, 17c of each cylinder 25 being directed toward a common center 18; and, as the centers 18 are, as in Fig. 5, in the plane of the longitudinal center line of the engine, air will flow in symmetrically from each side toward the centers 18 and upward flow will be better 30 controlled, as heretofore pointed out.

While the arrangements of scavenge air ports are effective to secure the operations pointed out, nevertheless, it may be desirable in some cases to prevent the possibility of short-circuiting of 35 scavenging air directly from the scavenge ports to the exhaust ports at the arcuate region of the cylinder nearest to the eccentric center 18. Accordingly, in Fig. 8, I show an alternative form of my invention wherein the circumferentially-extending row of exhaust ports 15 is incomplete, the exhaust ports in the arcuate region 30 nearest to the eccentric center 18 being omitted. The scavenge ports are radially disposed with the eccentric center 18 as described in connection 40 with Fig. 2.

From the foregoing, it will be apparent that I have provided an arrangement which gives effective and efficient scavenging with maximum 45 effective working stroke of the engine. As shown the scavenge air and exhaust ports are each arranged as a complete annular belt of closely spaced ports, whereby minimum cylinder length is required for their accommodation; and the complete belts or ports facilitate the maintenance 50 of adequate strength in the cylinder and provide for a more symmetrical structure. The complete annular belt of exhaust ports provides for effec-

tive discharge at high velocity all the way around the cylinder as soon as such ports are uncovered by the piston, this annular discharge of products of combustion induced by the pressure drop between the interior of the cylinder and the exhaust manifold continuing even after the scavenge air ports begin to open.

5 The scavenge air ports are arranged to promote effective scavenging, they being directed radially toward an eccentric center so as to secure 10 bunching of the air at the side of the cylinder adjacent to the eccentric center, the air moving upwardly as a column due to the resultant effect of its velocity energy, and the upwardly moving column is deflected by the cylinder head for movement 15 downwardly in a bunched manner at the other side to evict products of combustion through the exhaust ports. Thus, it will be seen that, by having the scavenge air ports directed toward an eccentric center, the kinetic energy of the entering 20 air is not dissipated in a turbulent manner without effectively scavenging the cylinder, but the preponderating effect of the velocity energy toward the side of the cylinder at the eccentric center provides an upwardly moving current of 25 air at the latter side. If desired, the directive tendency of the air may be aided by inclining upwardly or inwardly one or more of the scavenge air ports at the eccentric center side of the cylinder. It will also be seen that, by having the eccentric 30 centers in the plane of the engine center line, symmetrical flow of air into the cylinders and consequent better control of the upwardly moving air columns are provided for.

While I have shown my invention in several 35 forms, it will be obvious to those skilled in the art that it is not so limited but is susceptible of various other changes and modifications without departing from the spirit thereof, and I desire, therefore, that only such limitations shall be placed there- 40 upon as are imposed by the prior art or as are specifically set forth in the appended claims.

What I claim is:

1. In a two-cycle engine, a cylinder, complete and superposed annular belts of exhaust and 45 scavenge ports extending through the cylinder wall and a piston uncovering the exhaust and scavenge ports successively at the end of each working stroke, the scavenge ports being disposed substantially radially converging toward a center 50 which is eccentric to the cylinder axis.

2. The combination as claimed in claim 1 with at least the scavenge port or ports at the side of the cylinder adjacent to the eccentric center inclined upwardly and inwardly. 55

EDWARD S. DENNISON.
